AUTOMOBILE LAMP

Henry T. King and Edwin S. Getner, Detroit, Mich., assignors to Chrysler Corporation, Highland Park, Mich., a corporation of Delaware

Application July 22, 1954, Serial No. 31,539

Term of patent 7 years

(Cl. D48—32)

To all whom it may concern:

Be it known that we, Henry T. King and Edwin S. Getner, citizens of the United States, residing in the city of Detroit, county of Wayne, and State of Michigan, have invented a new, original, and ornamental Design for an Automobile Lamp, of which the following is a specification, reference being had to the accompanying drawing, forming part thereof, in which:

Fig. 1 is a front elevational view of an automobile lamp showing our novel design;

Fig. 2 is a side elevational view thereof; and Fig. 3 is a top plan view thereof.

We claim:

The ornamental design for an automobile lamp, substantially as shown.
